H. L. FISCHER

COMBINED INKWELL AND PEN SUPPORT

Filed June 4, 1926

FIG.1

FIG.2

Inventor:

Horand Fischer

Patented Nov. 30, 1926.

Des. 71,552

UNITED STATES PATENT OFFICE.

HOWARD L. FISCHER, OF ST. PAUL, MINNESOTA.

DESIGN FOR A COMBINED INKWELL AND PEN SUPPORT.

Application filed June 4, 1926. Serial No. 17,932. Term of patent 14 years.

To all whom it may concern:

Be it known that I, HOWARD L. FISCHER, a citizen of the United States, residing at St. Paul, county of Ramsey, and State of Minnesota, have invented a new, original, and ornamental Design for Combined Inkwell and Pen Support, of which the following is a specification, reference being had to the accompanying drawing, forming part thereof.

In the drawings:

Figure 1 is a perspective view of a combined ink well and pen support, showing my new design.

Figure 2 is the side elevation of the combined ink well and pen support, showing my new design.

I claim:

The ornamental design for a combined inkwell and pen support as shown.

HOWARD L. FISCHER.
